LAURENCE A. HAWKINS, OF SCHENECTADY, NEW YORK, ASSIGNOR, BY MESNE ASSIGNMENTS, TO THE UNION SWITCH AND SIGNAL COMPANY, A CORPORATION OF PENNSYLVANIA.

BLOCK-SIGNAL SYSTEM.

1,188,273.

Specification of Letters Patent. Patented June 20, 1916.

Application filed June 6, 1908, Serial No. 437,065. Renewed April 28, 1911. Serial No. 623,969.

To all whom it may concern:

Be it known that I, LAURENCE A. HAWKINS, a citizen of the United States, residing at Schenectady, county of Schenectady, 5 State of New York, have invented certain new and useful Improvements in Block-Signal Systems, of which the following is a specification.

My invention relates to block signal systems for railways like the ordinary electric railway, having both rails conductively continuous for all currents, and its object is to provide an efficient, reliable and simple signal system for use on such roads.

10 In a prior application, Serial No. 435,861, filed June 1, 1908, I have explained how the skin effect in a rail traversed by alternating current may be utilized in a signal system by connecting the track relays in shunt to a short length of rail. In that application all the sources of alternating current connected to the rails were of the same frequency and phase and closed paths for the signal current were formed by impedances across the rails between the sources. 15 In my present system the sources themselves form the only connections across the rails, and adjacent sources supply currents of different character, so that two adjacent sources with the rails between them form a closed circuit traversed by a resultant current made up of the two component currents furnished by the two sources, respectively. As will hereinafter be explained, 20 the difference in character of the currents supplied by adjacent sources may consist in difference in phase or in frequency.

While, in my former application, I disclosed relays each having a track winding 40 composed of two coils connected in shunt to two short lengths of rail opposite each other in the track, so that the power current in the two relay coils produced opposing effects, I pointed out certain advantages 45 from the omission of one of those coils in that particular system, and disclosed as a preferred form, and claimed, the one-coil arrangement. In my present system the two-coil arrangement possesses the advantage 50 above mentioned as to the effect of power current, and does not introduce any limitation, as in the former system. I consequently include as one feature of my present invention the two-coil arrangement of 55 the track windings of the relays.

My invention will best be understood by reference to the accompanying drawings, in which—

Figure 1 shows diagrammatically a block signal system arranged in accordance with my invention; Fig. 2 shows a modification of the same, having two frequencies in place of two phases supplied to the track circuits; and Fig. 3 shows a modification of the arrangement of Fig. 1, in which two relays 65 per block are employed.

In Fig. 1, A represents the track rails, which may be continuous throughout their length, as in an ordinary electric railway. B represents a two phase generator, which 70 supplies the current for the signal circuits. I have shown a three-wire transmission system supplied from this generator, the wire b serving as common return for both phases; one phase being connected between the wires 75 b and b¹, and the other phase being connected between the wires b and b². C, C¹ and C² represent transformers having their primaries connected to the transmission system and their secondaries connected 80 across the rails through impedances c. These impedances, which may be either inductive or non-inductive, serve to limit the current drawn from a transformer when a train stands on the track at the transformer. 85 Adjacent transformers have their primaries connected to different phases of the transmission system. D¹ and D² represent relays, which are shown as of the well known two-phase induction type, comprising a 90 movable short-circuited secondary member d, carrying the relay contacts, and two stationary coöperating windings d¹ and d². The winding d¹ preferably is composed of two coils, as shown, connected across two 95 short rail lengths opposite each other in the track, and adjacent to one of the transformers. A second winding d² of the relay is supplied independently of the track circuits by connection to the transmission wires 100 through a suitable phase controlling means indicated by the resistance d³. E¹ and E² represent signals controlled by the track relays.

When the blocks are unoccupied, a current 105 flows through the rails of each block and through the secondaries, in series, of the two transformers at the ends of the blocks, which current is the resultant of the current supplied to the rails by the two transformers at 110

the ends of the block. These two currents are displaced from each other ninety degrees in phase, so that the resultant current is displaced in phase forty-five degrees from 5 each component current. The winding d^2 of the relay D^1 is supplied from the same phase as the supply transformer C , and the resistance d^3 is so adjusted that the current in the relay winding d^2 is substantially in 10 phase with the component current in the track windings d^4 received from the transformer C . The current in winding d^2 of relay D^1 is thus ninety degrees out of phase with the current component received in 15 winding d^4 from transformer C^1 . Consequently, the current in winding d^2 co-operates only with the component current in winding d^4 received from transformer C^1 . With this 20 adjustment of the phases of the currents in the relay windings, it will be seen that a train approaching the block guarded by signal E^1 , the direction of traffic being as indicated by the arrow, will gradually short-circuit transformer C , but will not thereby 25 affect the relay torque, since its only effect on the current in the track winding is gradually to remove the component current received from transformer C , which component produces none of the relay torque. 30 With the front wheels of the train directly over transformer C , the track winding of relay D^1 is receiving only current from transformer C^1 , which is the current which actuates the relay. As soon as the front wheels 35 of the train have passed over the short rail lengths (50 or 100 feet, for instance) spanned by the relay track winding, the relay is totally de-energized, and the signal E^1 goes to danger. The point at which the 40 signal goes to danger is thus defined within the short rail length spanned by the track winding of the relay. As long as the train is in the block, the current from transformer C^1 is cut off from relay D^1 , and this relay 45 remains de-energized since it cannot be cleared by current from transformer C , which is of the wrong phase to operate it, and any current which may come from the transformer next beyond transformer C will 50 tend merely to hold the relay more firmly in stop position. This can best be seen by considering the effect of a train between transformers C^1 and C^2 . Any current from transformer C , passing transformer C^1 , will 55 flow in the opposite direction through winding d^4 of relay D^2 , from that in which the current from transformer C^2 flows. Consequently, its effect is to give the relay a 60 counter-torque, holding it in its de-energized position.

The advantage of employing two coils for winding d^1 for the relays is twofold. First, since the power current flows in the same direction in both rails, it produces opposing 65 effects in the two coils of the relay track

winding; and second, for a given amount of current in the rails and a given torque to be obtained in the relay, the distance spanned by the relay need be only one-half as much, if both rails are utilized, as would be required if the relay winding were connected in shunt to only one rail. Consequently the entering point of the block is more definitely defined. 70

Since each relay is close to a transformer, 75 to the current from which it must not respond, it is essential that the current in the winding d^2 of the relay should be carefully adjusted, so as to give either zero torque or a small counter-torque, when the current in 80 the track winding is supplied only from the adjacent transformer. Furthermore, the power factor of the impedance c , in series with the secondary of the transformer, must be properly selected. If the power factor of 85 this impedance is the same as that of the rails for the frequency employed, then the phase of the current delivered by the transformer is substantially the same when a train is in a block near the transformer, and 90 when the block is clear. On the other hand, an impedance of such a power factor may be selected that with the block clear and the current from the transformer consequently flowing through the entire rail length of the 95 block, the phase of the current delivered is such as to produce no torque in the relay; while with a train in the block close to the transformer, so that most of the rail impedance is out of circuit, the phase of the current delivered by the transformer is shifted 100 so as to give a counter-torque in the relay adjacent to it. 100

If, instead of relying on a difference of phase in the currents supplied to the track 105 by the transformers, a difference of frequencies is utilized, no careful adjustment of the relay is necessary, since, if the frequencies are properly selected, each relay will remain wholly unaffected by current, 110 except that from the source to which it is intended to respond. Such an arrangement is shown in Fig. 2, in which two two-phase generators B^1 and B^2 , of different frequency, are employed for furnishing the 115 signal current. I have shown a five-wire transmission system having a common return b , one phase of one generator being connected between wires b and b^1 , and the other phase between b and b^2 ; and the two 120 phases of the other generator connected between wires b and b^3 and between wires b and b^4 , respectively. The transformers C and C^2 are connected across one phase of generator B^1 , while transformer C^1 is connected across one phase of generator B^2 , so 125 that adjacent transformers supply to the track currents of different frequency. Consequently, there flows through the circuit formed by the secondaries of two adjacent 130

transformers and the rails between them a composite current formed of two component currents of different frequency. Transformers C and C² are similarly connected as in Fig. 1. The relays have their track windings connected as in Fig. 1, while their other windings are connected to the phases of the generators not connected to the supply transformers. Thus, relay winding d² 5 of relay D¹ has impressed upon it a voltage substantially in quadrature to that impressed upon the track by transformer C¹, and consequently the relay responds to the current from that transformer. Similarly, 10 the corresponding winding of relay D² has impressed upon it a voltage in quadrature to that impressed upon it by the transformer C². With the two-frequency arrangement of Fig. 2, it is practically essential to employ separate transmission wires 15 for supplying the windings d² of the track relays, since the secondary of each track transformer has flowing through it a current of another frequency than that of the voltage impressed upon its primary, and this current induces a corresponding frequency in the primary, so that if the windings d² were supplied from the same circuits as the primaries of the track 20 transformers, the winding d² of each relay would have impressed upon it a composite voltage comprising a small component voltage of the frequency to which the relay is not intended to respond. With the separate 25 circuits shown in Fig. 2, however, each relay is rendered absolutely independent of all currents except the one to which it is intended to respond.

One reason why it is necessary to adjust 30 the phase of the current in the winding d² carefully in the arrangement of Fig. 1, is that this relay is so much closer to the source of current to which it is not intended to respond than it is to the source of current to which it should respond, so that because of track leakage, the resultant current flowing through the relay windings has a component current to which it should not respond greater than the component current 35 to which it should respond. This disadvantage does not exist in the arrangement of Fig. 3, in which the relays are placed midway between two adjacent sources. This arrangement, however, requires two 40 relays per block, as is shown in the drawing. The transformers are placed in the centers of the blocks, and adjacent transformers are connected to different phases of the transmission system, as in Fig. 1. A relay is employed at each end of each block, the relays D and D¹ having their contacts connected in series to control the signal E¹, which guards the length of track between the relays. The track windings d², as in 45 Fig. 1, are connected to the other phase

from that to which the primary of the transformer to which they respond is connected. As in Fig. 1, each track circuit includes the secondaries of two adjacent transformers and the track rails between them. 70

The operation of the system will be evident from the drawing and from the description that has already been given of Fig. 1. With a train between relay D and transformer C¹, relay D¹ is deenergized, while with a train between transformer C¹ and relay D¹, the latter is deenergized. The relays are unaffected by the train, until the front wheels of the train pass over the short rail lengths spanned by the relay track windings, so that the point at which the signal goes to danger is marked in precisely the same way as in the preceding figures. It will be noted, however, that there is a difference in regard to the definiteness with which the outgoing end of each block is defined. In Fig. 1, for instance, the relay D¹ does not clear the instant the rear wheels of the train have passed transformer C¹, but remains deenergized until the train has passed transformer C¹ a sufficient distance to enable the secondary voltage of the transformer to rise to an amount sufficient to send through the rail circuit between this transformer and transformer C a current of great enough amount to clear the relay D¹. There is thus an overlap at the outgoing end of the block, which overlap is not absolutely definite. This overlap is not ordinarily a disadvantage, but, on the contrary, is an advantage, as affording additional protection. The arrangement of Fig. 3, however, defines the point at which the signal clears, as closely as the point at which the signal goes to danger is defined in all the modifications shown. The instant the back wheels of the train have passed from the short rail lengths spanned by winding d¹, relay D¹ is energized with its full torque, and consequently 100 the point at which the signal clears is defined within the short rail length spanned by the relay track winding. This arrangement is, therefore, especially advantageous where an exact definition of the block is desired at the outgoing end, as well as at the incoming end. Such an exact definition is desired for cross-overs and interlocking. 110

Other combinations of transformer and relay connections will be obvious to those skilled in the art. Accordingly, I do not desire to limit myself to the particular connections and arrangement of parts here shown, but aim in the appended claims to cover all modifications which are within the 115 scope of my invention.

I do not in this application make any claim to a block signal system for railways having both rails conductively continuous for all currents, in which adjacent sources 120

of current for the track circuits are of different character and the relays are selectively responsive to current of one character only, nor do I make any claim to a system 5 for such railways having the relays arranged in pairs between adjacent sources, since these matters form the subject-matter of my prior application, Serial No. 329,847, filed August 6, 1906.

10 What I claim as new and desire to secure by Letters Patent of the United States, is,—

15 1. In a block signal system, in combination with a railway having both rails conductively continuous for all currents, sources 20 of alternating current connected at intervals across the rails and forming the only electrical connections across the rails, adjacent sources being of different character and forming with each other and the intervening 25 rails a closed circuit traversed by the resultant of the currents delivered by said sources, track relays each operatively related to one of said closed circuits and responsive only to the flow through said circuit of current 30 from one of the sources comprised in said circuit, and signals controlled by said relays.

35 2. In a block signal system, in combination with a railway having both rails conductively continuous for all currents, sources 40 of alternating current connected at intervals across the rails, adjacent sources being of different character and forming with each other and the intervening rails a closed circuit traversed by the resultant of the currents delivered by said sources, track relays each operatively related to one of said closed 45 circuits, each of said relays being adjacent to one source and responsive only to current flowing through said circuit from the source 50 at the other end of said circuit, and signals controlled by said relays.

55 3. In a block signal system, in combination with a railway having both rails conductively continuous for all currents, sources 60 of alternating-current connected at intervals across the rails and forming the only electrical connections across the rails, adjacent sources being of different character and forming with each other and the intervening 65 rails a closed circuit traversed by the resultant of the currents delivered by said sources, track relays each having a winding connected in shunt to a short length of rail between two sources and responsive only to current 70 from one source, said length of rail being sufficient to provide the drop in voltage necessary to energize the relay, and signals controlled by said relays.

75 4. In a block signal system, in combination with a railway having both rails conductively continuous for all currents, sources of alternating-current connected at

intervals across the rails, adjacent sources being of different character and forming with each other and the intervening rails a 65 closed circuit traversed by the resultant of the currents delivered by said sources, track relays each having a winding connected in shunt to a short length of rail between two sources and each of said relays being adjacent to one source and responsive to current from the other source only, said length of rail being sufficient to provide the drop in voltage necessary to energize the relay and signals controlled by said relays. 70

75 5. In a block signal system, in combination with a railway having both rails conductively continuous for all currents, sources of alternating-current connected at intervals across the rails and forming the only 80 electrical connections across the rails, adjacent sources being of different character and forming with each other and the intervening rails a closed circuit traversed by the resultant of the currents delivered by said 85 sources, track relays each having a winding connected in shunt to a short length of rail between two sources, said length of rail being sufficient to provide the drop in voltage necessary to energize the relay, and each 90 relay having a second winding supplied independently of the track circuits with current adapted to coöperate only with the current received in the track winding from one source to actuate the relay, and signals controlled by said relays. 95

100 6. In a block signal system, in combination with a railway having both rails conductively continuous for all currents, sources of alternating-current connected at 105 intervals across the rails, adjacent sources being of different character and forming with each other and the intervening rails a closed circuit traversed by the resultant of the currents delivered by said sources, track 110 relays each having a winding connected in shunt to a short length of rail between two sources and each of said relays being adjacent to one source, said length of rail being sufficient to provide the drop in voltage necessary to energize the relay, and each relay having a second winding supplied independently of the track circuits with current adapted to coöperate only with the current received in the track winding from the other 115 source to actuate the relay, and signals controlled by said relays.

in witness whereof, I have hereunto set my hand this 5th day of June, 1908.

LAURENCE A. HAWKINS.
